DELTA-STAR ELECTRIC COMPANY, OF CHICAGO, ILLINOIS, A CORPORATION OF
ILLINOIS

ROTARY SWITCH

Application filed June 14, 1927. Serial No. 198,769.

Our invention pertains to electrical switches and more particularly to rotary switches.

We propose to provide an improved outdoor type of rotary switch including essentially a pair of spaced terminals, a rotatable blade cooperable therewith, and a mounting for the blade positioned between the terminals. The blade is of such a construction as is commonly actuated manually by means of 10 an operating arm or crank.

Now it will be appreciated that in the operation of the switch blade considerable friction must be overcome due to the sliding engagement between the ends of the blade and the 15 terminals. If the switch is large it is only with great exertion that the operator can open or close the switch. In opening the rotary switch the operator must, of necessity, exert considerable force upon the blade initially in order to overcome the friction between the sliding blade and the terminals. Once the blade is clear of the terminals it may be turned with facility. Similarly, when the operator closes the switch he must, at the latter 20 part of the movement of the blade, overcome once again the friction incident to the ends of the blade sliding on the terminals. Thus it will be evident that the operation of the switch would be much easier if this sliding engagement was eliminated.

We have provided a switch wherein this sliding engagement of the blade upon the terminals is eliminated. The blade, in being moved to its open position, is first moved in 25 a direction parallel with its mounting until the blade ends are entirely clear of the terminals. Thereafter, the blade is rotated away from the terminals. On the other hand, in closing the switch the blade is first rotated 30 into a position wherein its ends are properly aligned with the terminals and thereafter the blade is plunged into a quick and positive engagement with the terminals.

Another object of my invention is to provide novel means for protecting the terminal from the deteriorating effects of the sleet, snow, and rain. This preferably takes the form of a shield which we term a sleet shield. One of these shields is associated with each 35 of the terminals and it serves to prevent the

end of the switch blade from being frozen to the terminal. Also, when the blade end is clear of the terminal the sleet shield serves to prevent the natural elements from marring the contact surface of the same.

In accordance with the general features of our invention, we mount the switch blade upon a rotatable insulator. Associated with one end of the insulator is the rotary mounting of our invention. This mounting permits 55 of the insulator being moved in the direction of its axis, as well as being rotated.

In accordance with other features of my invention, we mount in each end of the switch blade a laminated contact mechanism adapted 60 to cooperate with the contact surface of the associated terminal. The end of the blade also has a protecting hood portion disposed about the contact mechanism in such a manner that the mechanism is only accessible 65 from below.

Still another feature of our invention is the provision of an adjustable connection between the rotatable insulator and the switch blade. This connection or mounting enables the 70 blades to be suitably adjusted and aligned with respect to the spaced terminals.

Other objects and advantages of our invention will more fully appear from the following detailed description taken in connection 75 with the accompanying drawings which illustrate several embodiments thereof and, in which:—

Figure 1 is an elevation of the preferred 80 form of our rotary switch;

Figure 2 is a plan elevation of the switch shown in Figure 1;

Figure 3 is a fragmentary sectional view drawn to an enlarged scale and taken on substantially the line 3—3 of Figure 2 looking 85 upwardly;

Figure 4 is a cross sectional view taken on the line 4—4 of Figure 3 looking in the direction indicated by the arrows;

Figure 5 is a sectional view taken on the line 5—5 of Figure 3 looking in the direction indicated by the arrows;

50 Figure 16 is a fragmentary plan elevation of the switch shown in Figure 15;

55 Figure 17 is an enlarged fragmentary sectional view taken on substantially the line 17—17 of Figure 16, illustrating another form of contact mechanism for establishing contact between the end of the blade and the terminal; and

60 Figure 18 is a fragmentary sectional view taken on the line 18—18 of Figure 15 looking in the direction indicated by the arrows and drawn to an enlarged scale.

65 Referring now to the drawings in detail, in which like reference numerals designate similar parts throughout the several views, 20 denotes a tubular member or switch blade (Figure 1). The blade 20 is positioned above three spaced insulators 21, 22 and 23. The blade 20 is rigidly fastened to the upper end of the insulator 22 which we term the rotary insulator.

70 We shall now proceed to describe in detail the mounting carried by the insulator 22 for the tubular blade 20.

75 Formed integral with the upper end of the insulator 22 is an iron member 24 preferably annular in shape. Positioned on this member 24 is a blade support or adapter 25 upon which the blade 20 is disposed in a longitudinal position. The adapter 25 (Figure 3) includes an annular portion 26 of a diameter 80 slightly larger than that of the top of the member 24. Projecting downwardly from the portion 26 is an annular flange 27 which surrounds the upper edge of member 24. The support 25 is fastened to the member 24 85 by means of bolts 28 threaded into the top

90 of the member 24. Each of these bolts 28 extends through a threaded aperture 29 as well as through a small bushing 30. The lower end of each bushing abuts the top of the member 24, whereas its upper end is 95 threaded into the aperture 29. The bushing 30 surrounds the shank of the bolt 28 and has its uppermost end provided with a screw driver slot 31. Now as will become more apparent hereinafter, it is possible by removing 100 the bolts 28 to turn the bushings 30 for the purpose of adjusting the position of the support 25 upon the member 24 so as to align the ends of the blade 20 with the terminals.

105 Extending laterally from the portion 26 are a pair of diametrically opposed projections 33 and 34, the end of each projection 33—34 being provided with a pair of spaced flanges 35 and 36 which define a pocket or a seat for the blade 20. In Figure 4 we have 110 designated the pocket or seat by the reference character 37. The flanges 35 and the flanges 36 of the mounting 25 are connected by longitudinal ribs 39 and 40 which extend parallel to the blade 20 (Figure 5). The ribs 115 39 and 40 are each provided with an arcuate shape for accommodating the periphery of the blade 20 as is evident from Figures 3, 4 and 5. Furthermore, it will be obvious from 120 Figure 3 that the flanges 39 and 40 extend across the top of the portion 26 so as to afford support for the blade between the ends of the two projections 33 and 34.

125 The blade 20 is fastened to the flanges 35 and 36 by means of a clamping member 41 provided with flanges 43 and 44 cooperable with the flanges 35 and 36. Bolts 45 extend through the flanges 43 and 44 and serve to tightly clamp the blade 20 against the seat 37 provided in the free end of the associated extension or projection 33—34. It will be 130 also observed that the top portion of the blade 20 extends into a pocket 46 in the clamp member 41. Furthermore, the top of the blade 20 is engaged at points 47 and 48 by the two flanges 43 and 44. In the pocket 37 the blade 20 is engaged at points 49 and 50 by the flanges 35 and 36. When the flanges 135 are tightly bolted together the points 47, 48, 49 and 50 tightly embrace the periphery of the blade 20. Thus it will be evident that we have provided a very rigid mounting for the intermediate part of the blade 20.

140 The ends of the blade 20 are adapted to be aligned with the terminals carried by the insulators 21 and 23. Since both of these terminals are identical, it is believed that a description of one will suffice for both. Incidentally, should it appear that the blade 20 does not quite align with the two terminals carried by the insulators 21 and 23, it is possible to adjust the blade with respect to its mounting 25 as previously mentioned. This adjustment is accomplished by removing 145 bolts 28 and by turning the bushings 30. 150

Each bushing may be turned with facility by means of a screw driver which may be inserted in the screw driver slot 31 provided in the top of the bushing. In Figure 2 it will be noted that the bolts 28 are positioned outside of the flanges 39 and 40, thus permitting of access to the bolts for the purpose of removing them with facility. The adjusting consists in varying the space separating the portion 26 from the top of the member 24.

10 The bushings 30 permit of the portion 26 being disposed at a slight angle with respect to the plane of the top of the portion 24. Thus if the blade 20 is slightly out of true it may be compensated for at the mounting 25.

15 The contact mechanism and the sleet shields of our invention are illustrated in detail in Figures 6, 7 and 8. Each free end of the blade 20 is telescoped by a tubular member 52 having formed integral with it a hood member 53 in which is disposed our novel contact mechanism designated generally by the reference character 55. The hood member protects the mechanism from sleet, 20 snow and rain. Also, the contact mechanism 55 (Figure 6) is only accessible from below.

25 Contact mechanism 55 is adapted to engage the top of a terminal plate 56 secured to a terminal member 57 fastened to the top 30 of the associated insulator 21-23. The plate 56 is preferably made of copper and has a lateral extension 58 fastened to an extension 59 formed integral with the terminal member 57. A tubular conductor 60 is firmly secured to the plate 58 by means of a clamping member 61 and by clamping bolts 62. It will be noted from Figure 6 that the plate 56 carries an arcuate shaped support 63 for the end of the conductor 60 and that 40 the blade is firmly gripped by the two members 61 and 63 which are tied together by the bolts 62.

35 The contact mechanism 55 includes a U-shaped channel 65 adapted to be reciprocated 45 between two pairs of webs 66 and 67 formed integral with the interior surface of the hood 53. The channel 65 is provided with an opening 68 through which extends a bolt 69 having its upper end threaded into a boss 50 70 formed integral with the cover 53. A small set screw 71 is threaded from the top of the cover 53 downwardly in the boss 70 and into engagement with the upper end of the bolt 69. This set screw 71 has a screw driver slot 72 by means of which the same 55 may be turned. The function of the set screw 71 is to lock the bolt 69 against rotation, as is evident from Figure 7.

60 Surrounding the shank of the bolt 69 and positioned between the top of the cover 53 and the channel 65 is a compression spring 74 which functions to at all times urge the channel 65 downwardly towards the copper plate 56. Referring now to Figure 6, it will be 65 noted that a flattened copper sleeve 75 abuts

the lower surface of the channel 65. This sleeve is flattened upon one end of a web-like conductor 76, preferably made of wire mesh. The conductor 76 is suitably fastened to the blade 20, and serves to establish an electrical connection between the contact mechanism and the blade 20. The shank of the bolt 69 extends through an opening 77 in the sleeve 75 and has a head portion 78 positioned between two laminated contact constructions 79 and 80. Each of the contact structures 79 and 80 comprises a plurality of laminations which may be made of any suitable material such, for example, as phosphor bronze. We have designated the laminations by reference character 81 (Figure 7). The laminations 81 each have substantially a U-shape and are piled one upon another as is clearly shown in Figures 6 and 7. The ends of the laminations engage the surface of the copper insert plate 56. Also the laminations 81 are secured to the bottom of the channel 65 by means of a clamp element 82 and a bolt and nut 83. Thus it will be evident that the pair of contacts 79 and 80 are urged into engagement with the top of the plate 56 by means of the spring 74. This spring permits the contacts to have a floating engagement with the contact plate.

65 Referring again to the hood portion 53 (Figure 7), it will be observed that one of its sides is provided with a downwardly extending flange portion 84 adapted to engage the side of the top member 57 on the insulator. This flange 84 serves as a stop for limiting the movement of the blade and for also insuring that the contact mechanism 55 will be properly aligned with the contact plate 57. Furthermore, we preferably provide one 70 end of the hood portion 53 (Figure 6) with a downwardly extending projection 85 spaced from the member 57. This projection serves to prevent sleet and rain from being blown into the interior of the hood 53. Moreover, it will be noted that the offset portion 58 of the contact plate 56 is disposed below the plane 75 of the contact plate 56. The purpose of this construction is to enable the contact arm or end of the plate 56 to be removed from the terminal without interference. However, in order to prevent the snow and sleet from being blown into the hood 53 from the outer end of the hood, we purposely extend the side 86 of the hood downwardly toward the extension 58 as is clearly shown in Figure 6. The side 81 of the hood opposite the flange 84 (Figure 7) is purposely made shorter than the other side as indicated at 87. That is to say, the end 85 of the side 87 is disposed a slight way above the top of the member 57 in order to prevent this side from engaging the contact plate 56.

80 As best shown in Figures 1, 2, and 8, a shield support member 90 is suitably fastened to the extension 59. Carried by this member 90 and disposed substantially parallel to the

top of the insulator, is a swivel bolt 91. This bolt is preferably secured to the member 90 by means of lock nuts 92. Pivotally mounted upon this bolt 91 is a sleet shield which comprises essentially a pair of pivotally connected plates 93 and 94 (Figure 8). We have designated the shield by the reference character 95.

The upper end of the sleet shield plate 94 is provided with two hinges 96 and 97 through which the bolt or pin 91 extends. Furthermore, the plate 94 is at all times urged downwardly by means of a spring 98, positioned between the hinges and encircling the intermediate portion of the bolt 91. The spring 98 is clearly shown in Figures 1 and 2. One end of the spring is anchored to the plate 94 and the other end is fastened to the bolt 91. The function of the spring is to urge the plate 94 at all times towards the position in which it is shown in Figure 8. In other words, the spring urges the plate 94 downwardly.

The two plates 93 and 94 are hinged together at 99. This hinge provides a pivotal connection between the two plates. We preferably form this hinge 99 by providing the plates 93 and 94 with socket portions for receiving a pivot pin 100. This arrangement is conventional in the hinge art. The free end of plate 93 is curved as indicated at 101. When the plate 93 is in the position shown in Figure 8 this curved portion 101 fits over the associated curved edge of the top member 57. Also plate 93 is provided with a pair of side flanges 102. Similarly, plate 94 is furnished with side flanges 103.

Now when the contact mechanism is in engagement with the plate 56 the hood portion 53 of the blade 20 will force the sleet shield 95 to the position shown in Figure 7. It will be observed from this position that the top of the hood 53 engages the plate 94 and holds it away from the insulator. However, when the contact mechanism is moved out of cooperation with the plate 56 the sleet shield 95 is caused to gravitate to the position shown in Figure 8. The spring 98 augments this movement of the shield. During this movement of the shield the ends of the plates pivot about the hinge pin 100 causing the plate 93 to be disposed immediately over the contact plate 56 for the purpose of protecting it from the effect of the natural elements.

Referring again to Figures 1 and 2 it will be observed that each of the insulators 21 and 23 has its lower end provided with a casting 105, preferably of iron, clamped to the flanges of a pair of spaced channel beams 106. The beams 106 are firmly clamped together by means of connecting plates 107. These plates 107 may be either bolted or riveted to the flanges of the beams 106. The channel beams 106 are disposed with their open sides facing each other. The beams

106 may be clamped to any suitable support such as a floor by means of the angle brackets 108 fastened to the sides of the beams.

We shall now proceed to describe in detail the operating mechanism carried by the 70 beams and associated with the lower end of the rotary insulator 22 for actuating the said insulator.

Referring to Figures 9 to 13, inclusive, it will be noted that the lower end of the insulator 22 is provided with a metal casting 110 having a flange 111 bolted to a flange 112 of a rotatable tubular element 114. The bolts for securing the two flanges 111 and 112 together are designated by the reference character 113 (Figure 9). The tubular member 114 extends downwardly into and telescopes a bearing member 115 having a flange 116. The flange 116 is secured by bolts and nuts 117 to the legs 118 of the channels 106. Also 85 the lower end of the member 115 is provided with a flange 119 secured by bolts 121 (Figure 10) to a gear casing 120.

Associated with the other legs 122 of the channels 106 are a pair of clamping elements 123 both of which are identical. These elements 123 not only serve to hold the member 115 downwardly in engagement with the legs 122, but also serve to prevent rotation of the member 115. Each of these elements 123 has a pair of lateral extensions 124 spaced a given distance apart. Extending into the space separating these projections 124 is a lug 125 formed integral with the flange 119 of member 115. Also each of the elements 123 is provided with a pair of circular apertures 126 into each of which is tightly fitted the shank of a bolt 127. The two bolts 127 serve to firmly fasten each clamping element 123 to its associated leg 122 of the channel 106. Furthermore, since the bolts 127 are tightly fitted in the openings 126 it must necessarily follow that when the bolts are tight the clamp elements 123 will be drawn bodily downward to firm contact with the flange 119 of member 115.

Positioned between the members 114 and 115 is a brass sleeve or tube 130, the lower end of which abuts a shoulder 131 formed in member 115. The upper end of tube 130 is provided with suitable openings 132 which communicate with an annular space 133 which constitutes an oil or grease pocket. Any suitable lubricating medium may be projected into the oil or grease space 133 by conventional mechanism such, for example, as a grease gun fitting. It will also be observed that the member 114 is provided with an annular recess 134 directly opposite the openings 132, which recess facilitates lubrication of the periphery of member 114. Extending upwardly into the member 114 is a shaft 135 the upper end of which is reduced at 136 and has mounted on its reduced end a threaded element 137. Element 137 is held against shoul-

der 138 on shaft 135 by means of a nut 139 threaded upon the extreme end 140 of shaft 135. Also, the element 137 is provided with a helical thread 141 which has a predetermined lead meeting the requirements of our particular type of switch. The inner wall of the member 114 adjacent the threaded element 137 is provided with an annular ring portion 142 equipped with a helical groove 143 adapted to mesh with the thread 141 on the element 137. The purpose of this helical groove construction will be more fully explained hereinafter.

The shaft 135 has an enlarged intermediate portion 144 and a slightly reduced portion 145 connected to the lower end of portion 144. Surrounding the portion 145 of shaft 135 are a pair of ball bearing units 146 and 147. The unit 146 is disposed upon an annular shoulder 148 formed in the member 115. This latter unit includes a pair of races 149 and 150 between which are disposed a plurality of anti-frictional elements or balls 151. Race 149 abuts the intermediate portion 135 and race 150 abuts the shoulder 148 on member 115. The unit 147 also includes a pair of races 152 and 153 between which are disposed a plurality of balls 154. The upper race 152 abuts the shoulder 155 formed on the member 115 and the lower race 153 abuts a collar 156 mounted on the reduced lower end 157 of shaft 135. The two ball bearing units 146 and 147 serve as both radial and thrust bearings.

The member 114 has a pair of substantially L-shaped slots or grooves 160 (Figure 10) each of which includes a horizontal leg 161 and a vertical leg 162 (Figure 9). Located in each slot 160 (Figure 12) is a roller 163 mounted on the end 164 of a trunnion bolt 165. The head 166 of the bolt is disposed on the exterior of the member 115, whereas the shank 165 is threaded into an opening 167 in the wall of the member 115. The side of each roller engages the intermediate portion 144 of shaft 135 as is obvious from Figure 12. These rollers are adapted to contemporaneously roll in the vertical leg 162 and thereafter in horizontal leg 161 and vice versa, depending upon the direction in which member 114 is being moved.

The extreme lower end 170 of shaft 135 is reduced and journaled at 171 in the boss 172 formed integral with casing 120. Splined to the portion 157 of shaft 135 is a worm wheel 173 which abuts the collar 156 and is held in place by means of a nut 174 threaded on the shaft. The worm wheel 173 is located in the casing 120 and meshes with a worm 175 disposed at right angles to the shaft 135. Worm 175 is located in an auxiliary casing designated generally by the reference character 176 (Fig. 11). The casing 120 has a pair of diametrically opposed flanges 177 and 178 which abut the sides of the elements 179

and 180. Each of the elements 170 and 180 telescopes the casing 176 and is equipped with flanges 181. The flanges 181 are secured to the associated flanges of the casing 120 as well as the casing 176 by means of bolts 182. The worm 175 is splined to a horizontal shaft 185 which may be actuated either manually or automatically. If it is so desired, a crank may be mounted upon an end of shaft 185 by means of which the switch may be operated. Also the shaft 185 is preferably common to a bank of three switches such as the switch we have disclosed.

In Figure 14 we have illustrated a slightly modified form of the operating mechanism. In this modification the slots 160' are disposed in the outer member 115' and not in the member 114'. Also the vertical leg 162' of each slot 160' extends downwardly from the horizontal leg 161'. The roller 163' is mounted upon a bolt 166' threaded at 167' into the wall of member 114'. This form of the invention is not as desirable as the form shown in Figure 12, inasmuch as the slots 160' are open to the atmosphere. The operation of this modification, however, is substantially like that of the form shown in Figure 12.

The operation of our switch is briefly as follows: When the switch blade 20 is in the engaged position shown in Figure 1, that is to say, in cooperation with the terminals carried by the two insulators 21 and 23, the rollers 163 will be in the position indicated in dotted lines in Figure 9. In other words, each roller 163, will turn in the vertical leg 162 of the associated slot 160. Now by turning the shaft 185 a rotary motion will be imparted to the shaft 135 within the member 114. This motion through the means of the threaded element 137 and the helical groove 143 on the inner wall of the member 114 causes the member 114 and the integral insulator 22 to be moved upwardly in a vertical direction. The rotary insulator 22 will continue to move in the vertical direction until the rollers 163 reach the horizontal legs 161 of the slots 160. By this time the contacts 79 and 80 associated with each end of the blade 20 will have been moved out of engagement with the associated terminal plates 56. Obviously, the blade 20 in being moved vertically also moves the hood or sleet shield 95 along with it. Furthermore, once the rollers 163 are in the horizontal legs 161 of the slots 160, the shaft 135 and the member 114 will rotate as a unit. This will result in the blade 20 being rotated away from the terminals.

As each end of the switch blade 20 leaves the associated terminal plate 56 the associated shield 95 is caused to gravitate until it reaches the position shown in Figure 8. In this position the plate 93 of the shield completely covers the contact or terminal plate 56 on top of the insulator.

When it is desired to move the blade 20 into

cooperation with the terminals carried by the two insulators 21 and 23, the shaft 185 is rotated in an opposite direction causing the vertical shaft 135 to turn therewith. In this movement of the shaft 135 the rollers 163 are caused to roll in the horizontal legs 161 of the slots 160. The rotation of member 114 results in the alignment of the vertical slot legs 162 with the rollers 163. Thereafter, the rollers 10 163 are caused to turn in the vertical legs 162 of the slots 160 due to the vertical movement of member 114. During this movement of the rollers the threaded portion 137 cooperates with the helical groove 143 to cause the 15 insulator 28 to be drawn downwardly thus bringing the ends of the blade 20 into cooperation with the terminals.

It will be evident from Figures 7 and 8 that when the end of the blade 20; namely, 20 the hood portion 53, comes into contact with the plate 94 of the shield 95 the shield will be moved out of cooperation with the terminal plate 56 and into the position shown in Figure 7. When the shield is in the position 25 shown in Figure 8 it serves to completely cover the plate 56, whereas when it is in the position shown in Figure 7 it functions to cover the end of the hood portion 53. As previously pointed out, the movement of the 30 blade is limited by the flange or stop portion 84 on the hood portion 53 (Figure 7) coming into engagement with the side of the member 57 on top of the insulator.

We shall now proceed to describe in detail 35 the modification of our invention shown in Figures 15 to 18, inclusive.

In this form of our invention the blade 220 comprises an I beam having its lateral flanges secured to the cast iron member 224 40 by means of bolts 225. The cast iron member may be secured in any desired manner to the rotary insulator 242. Also, the rotary insulator may be actuated by either of the two forms of operating mechanism previously 45 described. It will be evident from Figure 18 that each lateral flange 219 of the blade 220 is fastened by two bolts 225 to the member 224. The member 224 has a plurality of apertures 219' in which are disposed the 50 nuts 218' threaded on the shanks of the bolts 225. These apertures or openings 219' afford access to the nuts for the purpose of tightening them on the bolts.

Spaced from the rotary insulator 222 are 55 the fixed insulators 221 and 223. Each of these insulators carries a terminal 230' adapted to cooperate with an end of the blade 220. Also each end of the blade has its top edge tapering downwardly as indicated at 228. 60 Moreover, fastening to the base of the I-beam or blade 220 is a copper plate 230 which insures a good contact between the terminals and the blade. This plate may be either riveted or bolted to the beam 220.

65 Terminals 230' (Figure 17) include a

plate portion 235 fastened to the top of the associated fixed insulator by means of a bolt 236. Formed integral with the plate 235 is a lateral extension 237 to which is fastened a hood 238 secured to the portion 237 by 70 means of a bolt 239. The hood 238 is angular in shape and extends over the end 228 of the blade. Spaced from the plate 235 is a floating blade 240 loosely mounted upon the shanks of bolts 241. The lower ends of the bolts 241 are threaded at 242 into the plate 235. Also surrounding each bolt is a spring 244. The function of each spring 244 is to at all times urge the plate 240 upwardly. These springs, in reality, provide a resilient mounting for the plate 240 and cushion the jars incident to the engagement of the plate by the blade 220.

Suitably fastened to the top of plate 240 is an iron member 245 to which is fastened a flattened copper sleeve 246. The sleeve 246 is flattened upon one end of a braided copper conductor 247. This conductor extends through an opening 248 in the hood 238 and is fastened outside of the hood to the extension 249 formed integral with the hood and fastened to the extension 237 of the plate 235. The end of the power line may be suitably fastened to the extension 249, thus securing a direct connection between the power line and the end of the blade. 95

It will be observed from Figures 15 and 17 that the hood 238 is not only a fixed construction but is also provided with one side that is open to the atmosphere so as to permit the 100 end of the blade 228 to be moved into cooperation with the terminal 230'. The floating construction carried by the plate 235 always secures a good electrical contact between the end of the blade and the structure 247.

In the operation of the form of our invention shown in Figures 15 to 18, inclusive, the blade 220 is initially moved vertically out of engagement with the terminal and thereafter it is rotated to its disengaged position. When it is desired to move the blade into cooperation with the terminals, it is first rotated into alignment with the terminals and thereafter it is drawn downwardly into engagement with the copper sleeves 246. 110

Now we desire it understood that although we have illustrated and described in detail the preferred forms of our invention, the invention is not to be thus limited but only in so far as defined by the scope and spirit 120 of the appended claims.

We claim:

1. In a switch, a switch blade, a protecting hood mounted on one end of the blade, said hood being open at one end, floating contact 125 mechanism mounted within said hood, and a terminal adapted to be engaged by said mechanism, said mechanism comprising a guide element connected to the hood, a member reciprocably mounted on said element, a con- 130

- tact element secured to said member, and resilient means between the member and said hood for urging the contact element toward the open end of the hood and into engagement with said terminal.
5. In a switch, a switch blade, a protecting hood mounted on one end of the blade, floating contact mechanism mounted within said hood, and a terminal adapted to be engaged by said mechanism, said mechanism comprising a guide element connected to the hood, a member reciprocably mounted on said element, laminated contact springs secured to said member, and a spring between the member and said hood for urging the contact springs into engagement with said terminal.
10. In a switch, a switch blade, a protecting hood mounted on one end of the blade, floating contact mechanism mounted within said hood, and a terminal adapted to be engaged by said mechanism, said mechanism including a guide element secured to the hood, a member reciprocably mounted on the said guide element, and a pair of contacts secured to the said member, one being disposed on each side of the guide element.
15. In a switch, a switch blade, a protecting hood mounted on one end of the blade, floating contact mechanism mounted within said hood, and a terminal adapted to be engaged by said mechanism, said mechanism including a floating member and a contact fastened to said member, said hood having a plurality of flanges formed on its interior for guiding the said floating member in its movement.
20. In a switch, a switch blade, a protecting hood mounted on one end of the blade, floating contact mechanism mounted within said hood, and a terminal adapted to be engaged by said mechanism, said mechanism including a floating member and a contact fastened to said member, said hood having a plurality of flanges formed on its interior for guiding the said floating member in its movement.
25. In a switch, a switch blade, a protecting hood mounted on one end of the blade, floating contact mechanism mounted within said hood, and a terminal adapted to be engaged by said mechanism, said mechanism including a channel element, said hood having formed therein a plurality of webs for guiding said channel element.
30. In a switch, a switch blade, a protecting hood associated with one end of the blade, contact mechanism mounted within said hood, and a terminal adapted to be engaged by said mechanism, said mechanism including a channel element, contacts fastened to the said element, and a spring interposed between the channel element and the hood for urging the contacts into engagement with the terminal.
35. In a switch, a switch blade, a protecting hood associated with one end of the blade, contact mechanism mounted within said hood, and a terminal adapted to be engaged by said mechanism, said mechanism including a channel element, contacts fastened to the said element, and a spring interposed between the channel element and the hood for urging the contacts into engagement with the terminal.
40. In a switch, a switch blade, a protecting hood associated with one end of the blade, contact mechanism mounted within said hood, and a terminal adapted to be engaged by said mechanism, said mechanism comprising a substantially U-shaped channel element, a plurality of laminated contacts fastened to said element, and a spring interposed between the element and the hood having one end seated between the flanges of the channel, said hood having webs for guiding the channel element.
45. In a switch, a switch blade, a protecting hood associated with one end of the blade, contact mechanism mounted within said hood, and a terminal adapted to be engaged by said mechanism, said mechanism including a guide element and a contact structure reciprocably mounted on said element for movement to and from the open end of the hood, said hood having a boss in which an end of the said guide element is mounted.
50. In a switch, a switch blade, a protecting hood associated with one end of the blade, contact mechanism mounted within said hood, and a terminal adapted to be engaged by said mechanism, said mechanism including a guide element secured to the hood, a member reciprocably mounted on the said guide element, and a pair of contacts secured to the said member, one being disposed on each side of the guide element.
55. In a switch, a switch blade, a protecting hood associated with one end of the blade, contact mechanism mounted within said hood, and a terminal adapted to be engaged by said mechanism, said mechanism including a floating member and a contact fastened to said member, said hood having a plurality of flanges formed on its interior for guiding the said floating member in its movement.
60. In a switch, a switch blade, a protecting hood associated with one end of the blade, contact mechanism mounted within said hood, and a terminal adapted to be engaged by said mechanism, said mechanism including a channel element, contacts fastened to the said element, and a spring interposed between the channel element and the hood for urging the contacts into engagement with the terminal.
65. In a switch, a switch blade, a protecting hood associated with one end of the blade, contact mechanism mounted within said hood, and a terminal adapted to be engaged by said mechanism, said mechanism including a guide element connected to the hood, a member reciprocably mounted on the said guide element, and a pair of contacts secured to the said member, one being disposed on each side of the guide element.
70. In a switch, a switch blade, a protecting hood associated with one end of the blade, contact mechanism mounted within said hood, and a terminal adapted to be engaged by said mechanism, said mechanism including a floating member and a plurality of sets of laminated spring contacts fastened to the said member.
75. In a switch, a switch blade, a protecting hood associated with one end of the blade, contact mechanism mounted within said hood, and a terminal adapted to be engaged by said mechanism, said mechanism including a guide element secured to the hood, a member reciprocably mounted on the said guide element, and a pair of contacts secured to the said member, one being disposed on each side of the guide element.
80. In a switch, a switch blade, a protecting hood associated with one end of the blade, contact mechanism mounted within said hood, and a terminal adapted to be engaged by said mechanism, said mechanism including a fixed guide element, a channel reciprocably mounted on said element, resilient means surrounding the guide element for urging the channel in a given direction, and a pair of contacts fastened to said channel one on each side of the element, each of said contacts comprising a plurality of substantially U-shaped laminations secured together by a common fastening element.
85. In a switch, a switch blade, and contact mechanism associated therewith comprising a fixed guide element, a channel reciprocably mounted on said element, resilient means surrounding the guide element for urging the channel in a given direction, and a pair of contacts fastened to said channel one on each side of the element, each of said contacts comprising a plurality of substantially U-shaped laminations secured together by a common fastening element.
90. In a switch, an insulator including a top member having a recessed portion, a terminal including a plate disposed in said recess and having a lateral extension, said top member having an extension disposed under the plate extension for supporting the same, and an electrical conductor connected to said plate extension.
95. In a switch, an insulator including a top member having a recessed portion, a terminal including a plate disposed in said recess and having a lateral extension, said top member having an extension disposed under the plate extension for supporting the same, and an electrical conductor connected to said plate extension.
100. In a switch, an insulator including a top member having a recessed portion, a terminal including a plate disposed in said recess and having a lateral extension, said top member having an extension disposed under the plate extension for supporting the same, and an electrical conductor connected to said plate extension.
105. In a switch, an insulator including a top member having a recessed portion, a terminal including a plate disposed in said recess and having a lateral extension, said top member having an extension disposed under the plate extension for supporting the same, and an electrical conductor connected to said plate extension, and clamping means for rigidly securing the conductor to said extensions.
110. In a switch, a terminal, and a sleet shield for covering said terminal including a plurality of pivotally connected parts.
115. In a switch, a terminal, and a sleet shield for covering said terminal including a pair of plates one of which is pivotally connected to the terminal and a pivotal connection between the plates.
120. In a switch, a terminal, and a sleet shield for covering said terminal including a plurality of plates and a hinge connection between the plates, each of said plates having a side flange.
125. In a switch, a terminal, and a sleet shield therefor including a pair of pivotally connected parts, said parts being movable to bring one of said parts directly onto the top of the terminal.
130. In a switch, a terminal, and a sleet shield for covering said terminal including a plurality of plates and a hinge connection between the plates, each of said plates having a side flange.

shield therefor including a pair of pivotally connected parts, said parts being movable so that when one of said parts is at right angles to the other it will be resting on the top of the terminal.

18. In a switch, a blade, a terminal cooperable therewith, a sleet shield therefor, and a support for the sleet shield, said shield including a pair of plates and a pivotal connection between them, one of said plates being connected to the support and the other being adapted to be flush with the terminal when the blade is clear of the terminal.

19. In a switch, an insulator, a blade mounting carried by the insulator, a blade on said mounting, terminals cooperable with the blade, said mounting including an element disposed on top of the insulator, and means for adjustably securing said element to said insulator, said adjustable means permitting the blade to be properly aligned with the terminals.

20. In a switch, an insulator, a blade mounting carried by the insulator, and a tubular blade on said mounting, said mounting comprising a cap portion fastened to the top of the insulator, a pair of lateral arms connected to said portion, said arms defining a substantially semi-annular trough for receiving the said blade, means for adjustably securing said cap portion to said insulator, and means for clamping the blade to the arms.

21. In a switch, a blade comprising a metallic tube, a protective hood construction abutting an end of the tube, and a sleeve connected to the hood and disposed in telescoping relation with said end of the tube.

22. In a switch, a blade comprising a metallic tube, and a protective hood associated with an end of the tube including a shoulder abutting said end of the tube and a sleeve portion for telescoping the tube.

23. In a switch, a blade, a terminal cooperable with an end of the blade, and a protective hood connected to said end of the blade and provided with an extension adapted to engage said terminal, said extension serving as a stop for limiting the movement of said blade in a given direction.

24. In a switch of the class described, a terminal, a rotary switch blade cooperable therewith, means for actuating said blade, and a support for the actuating means and blade comprising a pair of channels spaced from each other with their open sides facing each other, said actuating means including a tubular member having flanges connected to the flanges of said channels.

25. In a switch of the class described, a terminal, a rotary switch blade cooperable therewith, means for actuating said blade, a support for the actuating means and blade comprising a pair of channels spaced from each other with their open sides facing each other, said actuating means including a tu-

bular member having flanges connected to the flanges of said channels, and clamping means for connecting said flanges including a clamp element fastened to a flange of a channel and having a pair of spaced lugs for engaging a flange on said tubular member, said latter flange having a lug disposed between said spaced lugs and serving to resist rotary movement on the part of the tubular member.

26. In a switch of the class described, a terminal, a rotary switch blade cooperable therewith, means for actuating said blade, a support for the actuating means and blade comprising a pair of channels spaced from each other with their open sides facing each other, said actuating means including a tubular member having flanges connected to the flanges of said channels, a gear box fastened to a flange on said tubular member disposed below the channels, said actuating means including a worm wheel in said box and a worm for meshing with said wheel and disposed without said box, a shaft on which said worm is mounted, and a casing for the worm in which said shaft is journaled connected to said gear box.

27. In a switch of the class described, a terminal, a rotary switch blade cooperable therewith, means for actuating said blade, a support for the actuating means and blade comprising a pair of channels spaced from each other with their open sides facing each other, said actuating means including a tubular member having flanges connected to the flanges of said channels, a gear box fastened to a flange on said tubular member disposed below the channels, said actuating means including a worm wheel in said box and a worm for meshing with said wheel and disposed without said box, a shaft on which said worm is mounted, and a casing for the worm connected to said gear box, said last mentioned means including a readily detachable member in which said shaft is journaled.

28. In an electric switch, a switch blade having successive rectilinear and rotary movements, a housing carried by the switch blade, and a floating contact within the housing and having a movement with respect to the blade in the direction of rectilinear movement of the blade, said contact being mounted in said housing.

29. In an electric switch, a switch blade having successive rectilinear and rotary movements, a floating contact carried by the blade, said contact being mounted for movement with respect to the blade in the direction of the rectilinear movement of the blade.

30. In an electric switch, a stationary switch contact, a movable switch blade, a housing open at the lower end mounted on the switch blade, means for moving the open end of the housing adjacent the stationary

contact, a contact within the housing movable towards and away from the open end of the housing, and means for moving the last mentioned contact into engagement with the first mentioned contact.

31. In an electric switch, a stationary contact, a movable switch blade, a housing open at the lower end mounted on the switch blade, means for moving the open end of the housing adjacent the stationary contact, a contact within the housing movable towards and away from the open end of the housing, and means within the housing for resiliently urging the last mentioned contact towards the first mentioned contact.

32. In an electric switch, a switch blade, a contact housing at one end thereof, said housing being open at the bottom, a substantially flat contact within the housing adjacent the open end, and spring means within the housing for forcing the contact towards the open end of the housing.

33. In an electric switch, a stationary contact and a movable contact, and means for moving the contacts out of engagement with each other, said means including means for giving the movable contact a rectilinear movement at a substantial angle to the contacting surface, followed by a swinging movement.

34. In an electric switch, a switch contact, a sleet hood collapsed upon the contact, a second contact enclosed in a second sleet hood, means for moving the two contacts into engagement, said first hood being expanded by the movement of said second hood to form an enclosing covering for both of the contacts.

35. In an electric switch, a stationary contact, a sleet hood normally collapsed thereon, a second contact, a sleet hood therefor, and means for moving said contacts into switch-closing position, said collapsed hood being expanded by said movement to cover said other hood.

36. In a switch, the combination of two spaced insulator stacks, contacts carried by said stacks, an intermediate insulator stack positioned between said spaced stacks, a switch blade mounted at its center on said intermediate insulator stack, means for successively rotating and imparting a rectilinear motion to the switch blade to move the same towards and away from the contacts, the contact making and breaking movement being rectilinear whereby bending stresses in the insulator stacks are avoided, and spring mounted contacts at the ends of the switch blades for engagement with the first mentioned contacts, said spring mountings permitting a rectilinear movement of the blade contacts in the direction of rectilinear movement of the blade, thereby distributing the stress on the two sides of the intermediate insulator stack.

37. In a gang operated switching system, a plurality of movable insulators each for controlling the movement of one switch, a worm

and worm wheel for moving each insulator, all of the worms being interconnected for simultaneous operation, and means for independently shifting each worm with respect to its worm wheel to impart a small movement to the respective switches to align the switches with respect to one another.

38. A switch comprising a pair of insulated contacts, insulator supports for the contacts, a switch blade cooperating with said contacts to establish a circuit between them, means including a rotatable and axially movable insulating member supported between said supports and supporting said switch blade above said contacts, said blade being moved into and out of butting engagement with both of said contacts by the actuation of said means, said insulating member being placed under tension and the contact supports being placed under compression upon closure of the switch and said blade having a resilient yielding engagement with both of said contacts whereby excessive stresses in the insulating member are avoided in the event of a misalignment of one of said contacts.

39. A switch comprising a tubular element including means for securing the same to a support, an insulator supporting member fitting into the element and maintained by said element against tilting, said member including an internally threaded portion within the element, an operating member extending into said element and threaded into said supporting member, bearings between the tubular element and the operating member, and means between the contacting walls of the tubular element and the insulator supporting member for imparting a guided longitudinal and rotary motion to the insulator supporting member upon rotation of the operating member.

40. A switch comprising a pair of spaced contact supporting insulators, means including an actuating insulator disposed between the two and adapted to have a rotary and longitudinal motion imparted thereto to establish a connection between the contact supporting insulators, an actuator tending by a single movement to impart both motions to the actuating insulator, and means for guiding the motion of the actuating insulator throughout its entire range of travel to establish a definite single position of the actuating insulator for each position of the actuator.

41. A switch comprising a pair of spaced contact supporting insulators, means including an actuating insulator disposed between the two and adapted to have a rotary and longitudinal motion imparted thereto to establish a connection between the contact supporting insulators, an actuator tending by a single movement to impart both motions to the actuating insulator, and means for guiding the motion of the actuating insulator throughout its entire range of travel to es-

tablish a definite single position of the actuating insulator for each position of the actuator, said means including a pin and slot connection in engagement during the entire travel of the actuating insulator.

42. A switch comprising a pair of spaced parallel insulators, contacts mounted thereon, a rotatable and longitudinal movable insulator midway between and parallel to said first insulators, a switch blade supported by said movable insulator above said contacts and actuated by the movable insulator to establish a bridging circuit between said contacts, means for rotating said blade supporting insulator to bring the blade in a position above the contacts and thereafter moving the same longitudinally to bring the blade and the contacts into butting engagement, said contact supporting insulators being placed under compression and said rotatable insulator being placed under tension, said blade and contacts having an engagement yielding in the direction of longitudinal motion of the blade, thereby avoiding excessive stresses in the insulators in the event of a misalignment between either of the contacts and the blade.

43. An electric switch comprising a support, a pair of spaced insulators mounted on said support, contacts mounted on said insulators, a rotatable and longitudinally movable actuating insulator on said support and between said insulators, a switch blade carried by said actuating insulator and moved thereby into and out of circuit closing position with both of said contacts, the switch closing movement including a longitudinal motion towards the supports and said blade having a resilient engagement with both of said contacts which is yielding in the direction of movement of the actuating insulator whereby excessive stresses in the actuating insulator are avoided in the event of misalignment of the contacts, and the opening movement including a longitudinal motion away from the support, whereby if the contacts and the switch blade tend to stick together the actuating insulator is placed under compression and said first mentioned insulators are placed in tension.

44. An electric switch comprising a support, a pair of spaced insulators mounted on said support, contacts mounted on said insulators, a rotatable and longitudinally movable actuating insulator on said support and between said insulators, a switch blade carried by said actuating insulator and moved thereby into and out of circuit closing position with both of said contacts, the switch closing movement including a longitudinal motion towards the support and said blade having a resilient engagement with both of said contacts which is yielding in the direction of movement of the actuating insulator whereby excessive stresses in the actuating

insulator are avoided in the event of misalignment of the contacts, and the opening movement including a longitudinal motion away from the support, whereby if the contacts and the switch blade tend to stick together the actuating insulator is placed under compression and said first mentioned insulators are placed in tension, a stationary tubular guiding member mounted on the support for guiding the movement of the actuating insulator, a member supporting the actuating insulator and extending into the tubular member, and means including a slot in one of said members and a cooperating pin on the other member for guiding the movement of the insulator supporting member.

45. An electric switch comprising a support, a pair of spaced insulators mounted on said support, contacts mounted on said insulators, a rotatable and longitudinally movable actuating insulator on said support and between said insulators, a switch blade carried by said actuating insulator and moved thereby into and out of circuit closing position with both of said contacts, the switch closing movement including a longitudinal motion towards the support and said blade having a resilient engagement with both of said contacts which is yielding in the direction of movement of the actuating insulator whereby excessive stresses in the actuating insulator are avoided in the event of misalignment of the contacts, and the opening movement including a longitudinal motion away from the support, whereby if the contacts and the switch blade tend to stick together the actuating insulator is placed under compression and said first mentioned insulators are placed in tension, a stationary tubular guiding member mounted on the support for guiding the movement of the actuating insulator, a member supporting the actuating insulator and extending into the tubular member, means including a slot in one of said members and a cooperating pin on the other member for guiding the movement of the insulator supporting member, and means including an irreversible gearing located on the side of the pin and slot opposite the actuating insulator for actuating the insulator supporting member.

46. A switch comprising a tubular bearing, an insulator supporting member extending from one end thereof, an operating member extending from the opposite end thereof and telescoping with the supporting member, said insulator supporting member having guided linear motion and guided rotary motion, and means for rotating said operating member to impart said motions to the insulator supporting member.

In witness whereof, we hereunto subscribe our names this 9th day of June, 1927.

TONY VAN RYAN,
ALFRED ALSAKER.
